Patents Corporation, New York, N. Y., a cor-
poration of New York

Application January 23, 1931. Serial No. 510,599

12 Claims. (Cl. 179—171)

My invention relates to electric amplifiers utilizing discharge devices and more particularly to direct coupled vacuum tube amplifiers. Amplifiers of this type, in which a direct coupling is used for handing on the output energy of one amplifying unit or valve to the input circuit of a succeeding amplifying unit or valve, have lately become known in the art and were primarily designed for the amplification of direct or unilateral current variations, in which case the use of capacitative or inductive elements in the coupling path from one amplifying valve to the next amplifying valve becomes prohibitive, as these devices would block the direct current component of a unilateral current variation and transmit only the variation itself, superimposed on the direct component.

Direct coupled or direct current amplifiers of this type, on the other hand, also present great advantages when used for the amplification of pure alternating current variation, such as speech or musical currents operating a loud speaker, or the like. This advantage consists primarily in a considerably decreased tendency to produce distortion of the signal current shape in comparison with the well-known amplifiers as used in the art for this purpose, utilizing devices liable to produce distortion of the current wave shape, such as capacity or inductance elements in the coupling path from one amplifying unit or valve to the next amplifying unit in a cascade amplification system.

There exist, however, a number of inherent disadvantages of direct coupled amplifiers of the type referred to known in the art, which have hitherto made their application in practice a very limited one. A main disadvantage of direct coupled amplifiers of known design consists in a strong tendency to instability, which tendency increases rapidly as the number of amplifying stages or units is increased. In fact, it was found that two or three stages were the maximum limit which could be used to insure fairly efficient and dependable service in operation. It is obvious, especially when telephone or similar complex current variations are to be translated and amplified, that even the slightest tendency of the amplifier to become unstable renders its practical application completely prohibitive for such a purpose.

Accordingly, it is an object of my invention to provide a new amplifying circuit for a direct coupled cascade amplification system, which is devoid of the inherent disadvantage of such amplifiers as above stated and which insures in-

creased operating stability and dependability of service.

A more specific object of my invention is the provision of a Wheatstone bridge coupling arrangement for handing on the output energy of one amplifying valve in a cascade system to the input circuit of a succeeding valve, which consists substantially of ohmic resistors and in which the second valve is controlled by unbalancing of the bridge system, in accordance with variations of input currents applied to the first valve.

This and further objects and features of my invention will become more apparent by the following detailed description, taken with reference to the accompanying drawing, illustrating some practical embodiments of the novel inventive idea. I wish it to be understood, however, that the description and the exemplifications as given by the drawing should be illustrative only of the broader aspects and principle underlying the invention, as set forth in its broad scope in the appended claims.

In Figure 1 I have shown, for the sake of explanation and clearer understanding, a direct coupled amplifying circuit of known design, known in the art.

Figure 2 shows a circuit arrangement of Figure 1 in an analyzed form, chosen for the sake of clearer understanding.

Figures 3 and 4 represent respectively a working diagram and an analyzed circuit diagram of one form of embodiment of my invention.

Figure 5 is a theoretical diagram explaining the connection of the valves, according to Figures 3 and 4.

Figure 6 is a similar circuit diagram of an amplifier as shown in Figure 3, with three amplification stages, including a current supply arrangement from an alternating house current net work.

Figures 7 and 8 show respectively an alternative working and corresponding analyzed circuit for practicing my invention.

Similar reference numbers or characters identify respectively similar elements or entities throughout the different views of the drawing.

Referring more particularly to Figure 1, this illustrates a well-known direct coupled simple amplifying circuit, comprising two amplifying valves 1 and 2 of ordinary design and construction, having filament, grid and plate electrodes. A potentiometer 3, connected to a plate current supply source, as indicated by the plus and minus signs, serves for providing the operating and control potentials of the amplifying valves. As is

seen, both valves are arranged in series or staggered fashion in respect to the potentiometer, so that the resultant potentiometer voltage has to be equal to the voltage necessary for one valve multiplied by the number of valves used in cascade, which, in the present case, is two. The plate electrode of the second valve 2 is directly connected to the positive pole of the high voltage battery and the plate electrode of the first valve connected to an intermediary tap *c* on the potentiometer, in series with a resistor 4, commonly designated as coupling resistor. The cathode of the first valve is shown to be connected to the minus terminal *a* of the potentiometer. In order to prevent the high potential on the plate of the valve 1, which is directly connected to the grid of the succeeding valve 2, from affecting the grid of the valve 2, the cathode of the latter is connected to a suitable tap point *b* on the potentiometer at a negative potential in respect to the point *c*, so that the potential drop from *c* to *b* provides a suitable compensating potential difference between the grid and cathode of the valve 2, which neutralizes the effect of the high voltage plate potential of the valve 1 on the grid of valve 2. The input current variations are applied to the grid of the valve 1 at the terminals 5 and the corresponding amplified output currents occurring in the anode circuit of the valve 2 may be utilized to operate a translating device of any type, such as loud speaker, television receiver, etc. connected to the output terminals 6. This system corresponds to the well-known direct coupled amplifying system known in the art up to date. As already stated, this system has a number of inherent disadvantages, which consist primarily of a strong tendency to instability during operation, on account of reaction of one valve upon the preceding valve or valves, as becomes obvious from the circuit diagram, from which it may be gathered that the anode current of one valve, by passing through the common potentiometer 3, is bound to affect the voltage or current distribution of the preceding valves, which, as a simple analysis will show, results in a kind of reaction, which has the effect of shifting the operating point; that is, primarily the grid bias point of the preceding valve or valves, to either positive or negative values, so that, with sufficient reaction; that is, sufficiently strong plate current variations of the succeeding valve or valves, one valve in the system may become either entirely saturated and act as a current limiting device, or it may be entirely blocked through increased negative bias, thus, in both cases, acting as a complete stop for the transmission of energy through the amplifier. As is obvious, this effect is the more imminent the higher the number of amplifying valves connected in cascade; that is, the greater the final current variations, whereby the reaction effect will cumulatively increase and cause the amplifier to completely drift to a non-operative or unstable condition. It is for this reason that amplifiers of this type have been used for not more than 2 stages of amplification, to minimize its tendency to become unstable.

One means to overcome this disadvantage would be to use a potentiometer 3, which passes a current sufficiently high, as compared to the plate currents of the amplifying valves, so that the reaction effect becomes negligible. For practical purposes, about 1 ampere potentiometer current will be required, considering the plate current of the usual output or power valves, which is about 30-40 milliamperes. Assuming, for in-

stance, a three stage amplifier to require about 300 volts high potential voltage; that is, about 100 volts for each valve, the resistance of the potentiometer would have to be

$$\frac{300}{1} = 300 \text{ ohms.}$$

As the current heat dissipation in the resistance is equal to the square of the current multiplied by the resistance, the energy expenditure in the potentiometer alone would, in this example, be 300 watts, which is prohibitive in a radio receiver or the like apparatus. Therefore, it is necessary to use a potentiometer with considerably less current, in which case the amplifier again tends to become unstable through reaction of the plate currents of succeeding valves on the operation conditions of the preceding valves, as explained above. Therefore, in accordance with the invention, different means are provided for overcoming the instability effects inherent in amplifying systems of the type in question.

Referring to Figure 2, this represents the circuit of Figure 1 in an analyzed form, being substantially a Wheatstone bridge arrangement with three arms or legs, consisting of ohmic resistors and one leg being comprised by the input valve 1. The operating potential is applied to one pair of diagonal terminals *a* and *c* of the bridge system and the cathode and grid of the second valve is connected to the remaining pair of diagonal terminals of the bridge, as shown. The bridge in the normal state is slightly unbalanced, so as to provide the required negative operating grid bias for the second valve. When the input currents applied to the terminals 5 vary, this will produce a corresponding additional unbalancing of the bridge and, accordingly, a corresponding plate current variation of the second valve 2.

The operating stability of a direct coupled amplifying system is considerably increased in accordance with the invention by using a bridge arrangement comprised substantially by resistors and by associating with it the input valves, in such a manner as to produce the desired amount of unbalancing on the system, in accordance with the input signal variations.

This I have illustrated in the analytical diagram according to Figure 4, which illustrates a complete bridge system comprised of a resistor for each arm of the bridge and the input tube 1 connected in parallel to one of the arms. The working diagram for such a circuit is shown in Figure 3, which differs essentially from Figure 1, in that at least two potentiometers 3 and 7 respectively are provided connected in parallel to the high potential supply terminals. The plates and cathodes of the individual valves are then connected to suitable points respectively to each of these potentiometers, as illustrated. Assuming, for the sake of explanation, the high potential voltage to be 200 volts and a voltage of 100 volts each to be required by each of the valves, the plate of the first valve 1 is connected to a point *f* on the upper potentiometer 7, which carries a potential of about 100 volts and the plate of the second valve 2 is connected to the plus terminal of the high voltage battery. The filament of the second valve is connected to a point *e* on the lower potentiometer 3, which is somewhat ahead of the 100 volt potential point—say at about 105 volts, so that the effective plate potential of the valve 2 is 95 volt and its negative grid bias equal to the difference of the plate potential of valve 1 and the filament po-

tential of valve 2; that is, equal to 100 minus 105 = -5 volts, which it is assumed corresponds to an efficient and favorable operating point on the rectilinear grid voltage-plate current characteristic of the valve. By suitably adjusting the taps *e* or *f* on the potentiometers 3 or 7 respectively, it is obvious that any desired negative biasing voltage may be readily adjusted. The same may be done for the valve 1 by adjusting the 10 tap points *d* and *g* respectively on the potentiometers 3 and 7, as shown. This is still further explained by Figure 5, in which the two parallel horizontal lines represent the levels of potential as supplied by the high potential source 15 and the two dotted horizontal lines *x* and *y*, also shown in Figure 3, represent the levels of potential as applied to the plate of valve 1 and grid of valve 2 respectively and to the filament of the valve 2. The difference in level between 20 *x* and *y* has to be chosen so as to present the proper operating bias for valve 2.

Referring to Figure 6, I have illustrated a complete operating circuit of a direct coupled amplifier, in accordance with the invention, which may 25 be operated directly from an alternating current net work supply, indicated at 17. The circuit according to this figure comprises three amplifying valves 1, 2 and 8 connected in cascade, in a manner similar to Figure 3. The filaments of 30 the valves 9, 10 and 11 are supplied each from the secondary windings 14, 13 and 12 respectively of an input transformer 15, these secondary windings being tapped at their mid-points in accordance with the well known practice, the mid-tap 35 points serving as cathode terminals for the valves and, accordingly, being connected to suitable tap points on the potentiometer 3, in accordance with the spirit of Figure 3. The plate potential voltage is supplied by the further secondary 18 of the input transformer 15, in combination with a rectifier 20 and a smoothing arrangement, the latter being comprised in the usual manner by shunt capacities 22 and 23 and a series inductance 21.

Referring to Figures 7 and 8, I have illustrated an alternative method of practicing the invention by using a push-pull arrangement for the output valves, as is most clearly seen from Figure 50 8, which distinguishes from Figure 4 in that two valves 2 and 8, arranged in push-pull fashion, are connected between the high potential diagonal terminals of the bridge system. Each of the grids of the two push-pull valves is connected to one of the remaining diagonal bridge 55 points *f* and *e* and the input valve 1 is again arranged in shunt relation to one of the bridge arms, to produce the unbalance and, accordingly, the variation of the plate current of the push-pull output valves. The output translating device, such as loud speaker, telephone, etc., may be either connected to the ends of a resistance 24 adjoining the anodes of the push-pull valves and being tapped at its mid-point for the positive potential supply, as is shown in Figure 8. In 60 this case, it is necessary that the resistance of the translating device, such as loud speaker, is properly designed and adapted for the resistor 24, or vice versa. As an alternative, an audio frequency push-pull transformer 19, of known 65 design, may be used in the plate circuit of the push-pull valves, as shown in Figure 7 and the output translating device connected to the secondary terminals 6 of the transformer, in a well-known manner. The connection of the valves to 70 the potentiometers 3 and 7 is seen from Figure 7

and is made in a similar manner to Figure 3 and in accordance with the diagram of Figure 8.

It is also possible to dispense with the part *g* of the potentiometer 7 according to Figure 7 and it is furthermore possible, as will be obvious, to combine a push-pull valve circuit with the known circuit according to Figures 1 and 2, in which case the advantage is also obtained of no reaction taking place on the input valve, depending on current changes of the succeeding valve 85 or valves.

It is obvious that many other modifications of my invention are possible, which come under its broader spirit and scope, comprising a bridge system arrangement substantially comprised by resistor elements with the input valve associated therewith, in such a manner as to bring about variable unbalancing of the bridge system, in accordance with the input current variations.

What I claim is:—

1. In a cascade amplification system, comprising a first valve, a second valve to be controlled by said first valve, a direct conductive coupling connection from the output electrode of said first valve to the input electrode of said second valve, a 100 Wheatstone bridge arrangement consisting of two pairs of balanced resistance arms, said first valve being connected to produce an unbalancing of said bridge system in accordance with input current variations, a common high potential operating source for said valves applied to a pair of diagonal points of said bridge system, the remaining pair of diagonal points of said bridge being connected to the input electrodes of said second valve.

2. In an amplification system, a first valve, a second valve to be controlled by said first valve, a direct conductive coupling connection from the output electrode of said first valve to the input electrode of said second valve, a Wheatstone 115 bridge arrangement comprising two pairs of balanced resistance arms, a high potential source connected to a pair of diagonal points of said bridge for supplying plate current for both of said valves, said first valve being furthermore associated with one of said bridge arms to produce an unbalancing of said bridge and said second valve having its input controlled in accordance with potential variations occurring between the remaining pair of diagonal points of said bridge, said system being normally unbalanced for producing a proper operating potential bias for said second valve and means for producing an additional unbalancing of said bridge system by said first valve, in accordance with input current variations.

3. In a cascade amplification system, comprising a first valve, a second valve to be controlled by said first valve, a direct conductive coupling connection from the output electrode of said first valve to the input electrode of said second valve, a Wheatstone bridge arrangement comprised of two pairs of balanced resistances, a high potential plate current source for both of said valves connected to one pair of diagonal terminals of said bridge system, the grid bias potential of the second valve being determined by the potential difference existing between the remaining pair of diagonal points of said bridge system and means for producing an unbalancing of said bridge system by said first valve in accordance with input current variations applied to said first valve.

4. In an amplification system, comprising a first valve, a second valve to be controlled by said first valve, a direct conductive coupling connection from

the output electrode of said first valve to the input electrode of said second valve, a Wheatstone bridge arrangement comprised of two pairs of balanced resistances, a high potential plate current source for both of said valves being connected to one pair of diagonal points of said bridge system, the grid potential of said second valve being determined by the potential difference existing between the remaining pair of diagonal terminals of said bridge system, said first valve being connected in shunt relationship to one of the resistance arms of said bridge to produce an unbalancing of same, in accordance with input current variations applied to the grid of said first valve.

5. In an amplification system, comprising a first valve, a second valve, each having cathode, grid and plate electrodes, a Wheatstone bridge arrangement comprised of two pairs of balanced resistances, a high potential plate current source for both of said valves applied to one pair of diagonal terminals of said bridge, a direct conductive coupling connection from the anode of said first valve to the grid of said second valve, further connections whereby the grid potential of said second valve is determined by the potential difference existing between the remaining pair of diagonal terminals of said bridge system and means for producing an unbalancing of said bridge system by said first valve, in accordance with input current variations applied to the grid of said first valve.

6. In an amplification system, comprising a first valve, a second valve to be controlled by said first valve, both of said valves including cathode, grid and plate electrodes, a Wheatstone bridge arrangement comprised of two pairs of balanced resistors, a plate current high potential source for both of said valves being applied to one pair of diagonal terminals of said bridge, a direct conductive coupling connection from the plate electrode of said first valve to the grid electrode of said second valve, connections whereby the grid bias voltage of said second valve is determined by the potential difference existing at the remaining pair of diagonal points of said bridge system and further connections whereby said first valve is arranged in shunt relationship to one of the resistance arms of said bridge for producing an unbalancing thereof in accordance with input current variations applied to the grid of said first valve.

7. In a cascade amplification system, comprising a first valve, a second valve to be controlled by said first valve, a plate potential source for both of said valves, at least two potentiometers connected across said plate potential source, connections from the plate electrodes of said valves to tap points on one of said potentiometers, further connections from the cathode electrodes of said valves to tap points on said other potentiometer and a direct conductive coupling connection from the plate electrode of said first valve to the grid electrode of said second valve.

8. In a cascade amplification system, comprising a first valve, a second valve to be controlled by said first valve, said valves having cathode, grid and plate electrodes, two potentiometers supplying a gradually varying operating potential, a direct conductive coupling connection from the plate electrode of said first valve to the grid

electrode of said second valve, connections from the plate electrodes of said valves to points on one of said potentiometers and further connections from the cathode electrodes of said valves to points on the other of said potentiometers.

9. In a cascade amplification system, comprising a first valve, a pair of output valves to be controlled by said first valve and connected in push-pull fashion, a balanced bridge system consisting of two pairs of balanced resistance arms, a common high potential operating source for said valves applied to a pair of diagonal points of said bridge, means for unbalancing said bridge in accordance with input current variations applied to said first valve, and connections from the control electrodes of said output valves to one of the remaining diagonal points each of said bridge system.

10. In a cascade amplification system, comprising a first valve, at least one pair of second valves connected in push-pull fashion and to be controlled by said first valve, a balanced bridge circuit comprised by two pairs of ohmic resistors with said first valve associated therewith to produce unbalancing of said bridge in accordance with input current variations applied to said first valve, a high potential operating source for said valves being applied to one pair of diagonal terminals of said bridge system and connections from the control electrodes of said push-pull valves each to one of the remaining diagonal points of said bridge system.

11. In a cascade amplification system, comprising a first valve, a pair of second valves connected in push-pull fashion and to be controlled by said first valve, said valves having cathode, grid and plate electrodes, a Wheatstone bridge circuit comprised of two pairs of balanced resistances, said first valve being connected in parallel to one of said resistances for producing an unbalancing of said bridge system in accordance with input current variations applied to said first valve, a common plate potential source for said valves applied to one pair of diagonal terminals of said bridge system, means including circuit connections to control the grid electrodes of said second valves in opposite phase relation in accordance with relative potential variations occurring between the remaining pair of diagonal terminals of said bridge system.

12. In a cascade amplification system, comprising a first valve, a pair of second valves connected in push-pull fashion and to be controlled by said first valve, a high potential operating source for said valves, at least one pair of potentiometers associated with said source for providing gradually varying potential drop, a direct conductive coupling connection from the control electrode of one of said push-pull valves to the plate electrode of said first valve, a further coupling connection from the control electrode of the remaining of said second valves to a tap point on one of said potentiometers, a further connection from the cathode electrodes of said valves to a further tap point on said last mentioned potentiometer and connections from the anode of said first valve and from the common anode terminal of said push-pull valves to points on the other of said potentiometers.

KARL RATH. 145
